UNITED STATES PATENT OFFICE.

WALTER R. PAXSON, OF GLENSIDE, PENNSYLVANIA, ASSIGNOR, BY MESNE ASSIGNMENTS, TO A. H. FOX GUN COMPANY, OF PHILADELPHIA, PENNSYLVANIA, A CORPORATION OF PENNSYLVANIA.

TOY SHOTGUN.

Application filed September 26, 1925. Serial No. 58,830.

This invention relates to toys, and more particularly to a toy gun simulating what is commercially known as a shotgun, an object of the invention being to provide a gun 5 either double or single barrel, which breaks at the breech for receiving a loaded shell from which a projectile is forced by the pulling of the trigger or one of the triggers of the gun, simulating in appearance and 10 operation a shotgun of standard make.

Another object of the invention is to provide a toy shotgun as specified, which is relatively simple in construction and in which the projectiles may be reloaded as 15 often as desired by the operator of the gun.

Another object of the invention is to provide in a toy gun as specified, a novel construction of barrel wherein the two barrels of a double-barreled gun have communication to permit the escape of air from one barrel into the other, to prevent the compression of air in the barrel and the resultant retarding action upon the projectile.

Other objects of the invention will appear in the following detail description, and in the accompanying drawings wherein:

Figure 1—is a side elevation of the improved gun.

Figure 2—is a horizontal section through 30 a part of the gun illustrating the trigger structure.

Figure 3—is an end elevational view of the gun with the barrels removed, the right hand half being shown in transverse cross-section.

Figure 4—is a detail cross section through the barrel taken on the line 4—4 of Figure 1.

Fig. 5—is a detail side elevational view 40 and an edge view of one trigger.

Figure 6—is a detailed side elevational view and an edge view of the other trigger.

Figure 7—is a longitudinal section through the shell used with the gun.

Figure 8—is an end elevation of the shell.

Figure 9—is a cross section through the shell.

Referring more particularly to the drawings, the improved gun comprises the stock 50 1 which is shaped to simulate the stock of shotguns of approved construction, and which has the barrels 2—2 connected thereto by any approved construction, such as

usually employed in shotgun structures to permit the placing of the shells 3, in the 55 breech of the barrels. The barrels 2 in a double barreled gun are formed of a single piece of sheet metal curved to provide the cylindrical barrels 4 and 5, with the edges of the sheet of metal turned inwardly and 60 spaced from the sight channel 6, as shown at 7, to provide means of communication between the two barrels 4 and 5, to prevent compression of air within either of the barrels upon the ejecting of a projectile. A 65 wire 8 is welded, soldered, or the like, between the barrels, to connect the inturned edges of the sheet of metal.

The shell structure 3 includes the cylindrical body 10 one end of which is inturned, 70 as shown at 11, to form a cartridge head which is provided with a relatively small central opening 12 over the outer edge of which the shoulder 13 on the tapered head 14 of the catch 15 engages, for retaining the 75 piston 16 to which the release pin 15 is connected, adjacent the rear end of the shell, thereby holding the spring 17 under tension. The piston 16 is provided with a plurality of small openings through the closed 80 end thereof to prevent any compression of the air in the body of the shell between the piston or plunger and the projectile and to prevent the forming of a vacuum or a partial vacuum within the shell in the rear of 85 said plunger. The projectile 18, which may be in the form of a ball, is held in the end of the shell 10 opposite the inturned end 11 by friction, and the resilient action of the shell body. The shell body is provided with an 90 annular groove 19 adjacent the projectile carrying end to provide sufficient friction for holding the projectile in place in the shell and prevents the piston from leaving the shell body 10.

When the shell is loaded, the piston 16 is in its innermost position with the shoulder 13 engaging over one edge of the opening 12, and the shell is placed in one of the barrels of the gun. When it is desired to 100 shoot the gun, either one of the triggers 20 are pulled, depending upon the barrel in which the shell is placed. The triggers 20 are slightly different in construction, but their function and general structure is the 105 same. The triggers 20 are pivotally mount-

ed upon a trigger pin 21 which extends through the hollow breech or frame mechanism carrying shell or frame 22. Firing pins 23 are connected to the upper ends 24 of the triggers providing a hammerless structure, and the firing pins project through the front plate 25. Spiral springs 26 are coiled about the firing pins 23 and engage against the front plate 25, and the shoulder 27 on the firing pins for holding the firing pins in their retracted position. When one of the triggers 20 is pulled rearwardly, the firing pin 23 connected thereto will be forced forwardly, and it will engage under the tapered head 14 on the pin 15, and force the pin upwardly releasing engagement of the shoulder 13, with the edge of the opening 12 and consequently, releasing the spring 17 which will force the piston 16 through the shell, to cause the said piston or plunger to strike the projectile 18, and force it from the barrel of the gun. The firing pin and trigger are returned to their normal positions by the springs 26. By particular reference to Figures 7, 8, and 9 of the drawings, it will be noted that the extreme point 28 of the tapered head 14 is on one side of the center line A of the shell body 10, and that the shoulder 13 is on the opposite side of said center line so that the tapered surface of said head always lies across the axis of said shell and of the firing pin, when the shell is in a barrel and the head 14 will be positively engaged by the tapered end 29 of the firing pin for releasing the piston 16 when the trigger is pulled.

The two barrels 2-2 are pivoted to the forward end of the frame in any suitable manner as by fore-end 30, the rear end of which is mounted on the pivot pin 31. In order that the rear end of the barrels 2-2 may be held firmly in alignment with the firing pins 23, the front plate 25 is bent to form a section 32 extending forwardly along the barrels and then downwardly to form a portion 33 extending to the inside surface of the frame 22. Then it is bent forwardly to form a portion 34 through which a pin 35 or other suitable fastening means are provided. The forward end of the section 34 is preferably provided with a curved concave edge 36 to form a stop against which the projection 30' of the fore-end strikes in breaking the gun at the breech.

The portion 32 corresponds to the water table of an ordinary shotgun and to hold the breech closed and the barrels against this water table 32, I provide the frame with a locking lever 37 mounted on a pivot pin 38 on the top side of the frame. This pivot is a stud or screw extending at right angles to the top surface of the frame 22 and the rear end of the lever is preferably provided with an upturned finger piece 39 by means of which

the said lever 37 may be swung horizontally with respect to the barrels until the forward end 40 clears the barrels. When the breech is closed by the locking lever 37 the forward end 40 preferably rests against the raised web 6 between the two barrels 2-2.

This front plate 25 fits into the forward end of the frame proper 22 and encloses the front of the frame adjacent the breech. A suitable space or gap is left between the rear end of the barrels and the front plate 25 for the reception of the flange of the shell or cartridge.

While the trigger guard 41 may be of any approved construction, I preferably provide the forward end thereof with a sharp bend 42 at an angle to the general direction of the guard and insert this bent end 41 through a suitable slot provided in the bottom side of the frame 22. The rear end of the guard may be secured to the stock by a screw 43 also extending through the lower finger 44 and into the stock 1 which is inserted into the rear end of the frame between the fingers 44 and 45. The upper finger may be similarly secured to the stock by a screw 43.

The upturned end of the lever 37 may be provided with a notch 46 to act as a sight when the lever is in operative position between the barrels closing the breech.

It will be seen that in making this gun I have made the frame, the triggers and the barrels all of thin material such as sheet metal stamped and shaped as desired and although the essential parts of the gun above described are thus made of this thin material, the gun as a whole when assembled constitutes in appearance a substantial miniature of a real shotgun.

It is, of course, to be understood, that the invention may be constructed in various other manners and the parts associated in different relations, and therefore, I do not desire to be limited in any manner, except as set forth in the claims hereunto appended.

What I claim is:

1. In a toy gun, a stock, a frame, a barrel carried thereby, a trigger, and means released by said trigger to impinge against a projectile in said barrel to impel said projectile forwardly out of said barrel at high speed, said barrel being provided with a longitudinal opening extending substantially throughout the length thereof to maintain atmospheric pressure behind said projectile during its travel through said barrel.

2. In a toy gun, a stock, a frame, a pair of barrels connected thereto, a pair of triggers, one for each barrel, and independent means in each barrel and released by said triggers to impinge upon a projectile in the barrel to impel said projectile forwardly out of said barrel at a high speed, said barrels being provided with longitudinal openings extending substantially throughout the

length thereof to maintain atmospheric pressure behind said projectile during its travel through a barrel.

3. In a toy gun, a stock, a frame, a pair of barrels connected thereto and provided with longitudinally extending openings to permit the lateral escape of air from the barrels and to maintain substantially atmospheric pressure behind the projectiles in their 10 passage through said barrels, said barrels being pivotally connected to said frame to permit the placing of shells in the breeches of the barrels, triggers carried by the frame, and means operated by said triggers for discharging the shells.

4. In a toy gun, a stock, a frame, a pair of barrels connected thereto and provided with longitudinally extending openings to permit the lateral escape of air from the 20 barrels, said barrels being pivotally connected to said frame to permit the placing of shells in the breeches of the barrels, spring pressed plungers in said shells, and pivoted triggers carried by said frame, and each 25 adapted for co-operation with a shell to release said plunger to discharge said shells.

5. In a toy gun, a stock, a frame, a pair of barrels connected thereto and having communication one with the other to permit the free movement of air from one barrel laterally into the other barrel when a 30 barrel is traversed by a projectile, and means to project a projectile through either barrel.

6. In a toy gun, a stock, a frame, double 35 barrels carried thereby and formed of a single piece of sheet metal shaped to provide parallel barrels, and having its edges inturned and positioned to permit passage of air from one barrel into the other.

7. In a toy gun, the combination of a stock, a frame, a pair of barrels pivotally connected thereto to permit the placing of shells in the breeches of the barrels, spring pressed plungers within said shells, means 40 in said shell to hold said plungers in a retracted position, and means carried by said frame for releasing said plungers to impinge against projectiles mounted in the forward ends of said shells and in said barrels respectively.

8. In a toy gun, the combination with a single piece of sheet metal bent to form a substantially cylindrical barrel, and a stock, of a rigid frame made of thin material, a 45 front plate secured within said frame, the edges of said frame adjacent said front plate following the contour of and substantially abutting the edges of the top and side portions of the rear end of said barrel and having a rearwardly extending portion forming a stock housing and having a transverse under portion providing a trigger guide and having a forwardly extending portion forming parallel braces fitting against the sides 55 of said barrel at the rear end thereof, means

for connecting said frame with said barrel and with said stock, including pins extending transversely through said frame, a trigger pivotally mounted within said frame, and a spring in said frame above said trigger 70 guide and operatively connected with said trigger and arranged to normally yieldingly hold the lower end of said trigger adjacent the forward end of said trigger guide.

9. In a toy gun, the combination with a single piece of sheet metal bent to form substantially cylindrical barrels with their axes parallel and with the opposite edges of said strip between said barrels, and a stock of a rigid frame made of thin material, having a 75 front plate within said frame, said frame presenting adjacent said front plate, flaring edges following the contour of and in registration with the edges of the top and side portions of the rear ends of said barrels and 80 having a rearwardly extending portion forming a stock housing shaped over and fitting around the forward end of the stock and having a transverse under portion providing trigger guides and having a forwardly 85 extending portion forming parallel braces fitting against the sides of said barrels at the rear ends thereof, means for connecting said frames with said barrels and with said stock, a trigger pivotally mounted within 90 said frame, and a spring in said frame above said trigger guides and operatively connecting the said trigger and arranged to normally yieldingly hold the lower end of said 95 trigger adjacent the forward end of said 100 trigger guide.

10. In a toy gun, a single strip of sheet metal bent longitudinally to form two like substantially cylindrical barrels with their axes in parallel relationship, said barrels 105 being connected at the top side by an integral web and the opposite edges of said strip being upturned beneath said web, and means between said barrels and below said edges to rigidly secure together adjacent 110 walls of said barrels.

11. In a toy gun, the combination of a barrel, a stock and a frame, said barrel being pivotally secured to said frame to form a breech at the rear end of said barrel for 115 the insertion of a toy cartridge, said frame being fitted around and secured to the forward end of said stock, the edge of the upper intermediate part of said frame being in substantial registration with the rear end of said 120 barrel, the forward part of said frame extending along the lower side of said barrel and providing a bearing at the end thereof for said barrel, a trigger pivotally mounted in said frame, said frame being provided 125 with a slot on the underside thereof through which the lower end of said trigger projects the forward movement of the lower end of the trigger, a front plate in said frame and provided with an opening in alignment with 130

said barrel, a firing-pin engaging the upper end of said trigger and slidably mounted in said opening in said front plate, and a spring to normally hold said pin at the rear-most limit of its longitudinal movement and the lower end of said trigger at the forward limit of its motion in said slot in said casing.

12. In a toy gun, the combination with a stock, a frame, a barrel connected to the frame to permit of the placing in the breech of the gun a shell, comprising a casing, a plunger within said casing, a spring, a detent for holding said plunger retracted at a position near the rear of said casing with said spring compressed against said plunger, a projectile retained in said casing at the open discharge end thereof and spaced from said plunger when said plunger is in retracted position, a stop in said casing to stop the forward movement of said plunger immediately after it strikes said projectile, a trigger mounted in said frame and a member in said frame in alinement with said shell and movable longitudinally by and in accordance with the trigger into and out of operative engagement with said detent and operable when advanced by said trigger to release said detent, whereby said plunger is impelled by said spring and strikes said projectile a sharp blow just prior to its engagement with said stop.

13. In a toy gun, the combination of a hollow gunlock frame formed of a plurality

of pieces of thin material rigidly secured together and having two parallel trigger slots therethrough and a gunlock mechanism mounted in said frame and comprising a pivot pin passing transversely through said frame, and two triggers mounted to turn freely on said pin and passing through said slots respectively, each slot forming a guide to position its trigger on said pin and a stop to limit the forward movement of the lower end of the trigger therein, one of the pieces of said frame forming the front plate of said gunlock mechanism, two firing pins extending through said front plate and operatively engaged by said triggers respectively, and a spring for each firing pin respectively and under tension to normally hold said firing pins retracted and the lower ends of said triggers in their most forward position.

14. In a double-barreled shotgun, the combination of a gunlock frame of thin material, a gunlock mechanism mounted therein and two barrels pivotally connected to said gunlock frame, said barrels being connected by a web and made of a single sheet of metal, the edges of the sheet metal of which said barrels are made being between the barrels and below and spaced from said web to form a longitudinal passage between said barrels for substantially the length of said barrels and a rod between said barrels and below said passage rigidly secured to said barrels.

In testimony whereof I affix my signature.
WALTER R. PAXSON.
